JOURNAL BOX LID

George B. Dorey, Westmount, Quebec, Canada

Application July 27, 1937, Serial No. 155,977

5 Claims. (Cl. 308—47)

My invention relates to improvements in journal box lids.

An object of my invention is to provide a two piece lid assembly of the spring actuated type which may be readily assembled without the use of special tools or power machinery to tension the spring.

Another object of my invention is to provide means for tensioning a lid spring in two easy stages by independently applying force to the respective relatively long ends of a double torsion spring.

Another further object of my invention is to provide a two piece lid assembly of the type having a pressure retaining spring associated with a lever hood and lid in such a manner that a hood retaining pintle will be maintained against axial movement by the lid proper and wherein the spring will operate to positively maintain the lid and hood in operative relation.

A more particular object of my invention is to provide means whereby a spring actuated two part lid assembly will have the spring pressure retained in combination with one of the parts of the assembly while the other part is being inserted or removed.

My invention further resides in certain other improvements and details of parts such as will be more fully pointed out hereinafter and claimed.

For further comprehension of my invention reference may be had to the accompanying drawings wherein:

Fig. 1 is a side elevational view of a portion of a journal box showing my improved lid applied thereto. Fig. 2 is a vertical end view of the lid shown in Fig. 1, and as viewed in said figure from left to right. Fig. 3 is a side elevational view of a journal box showing the hood in the open position and the spring indicated by full lines in the fully released position. Fig. 4 is a top plan view of the structure illustrated in Fig. 3. Fig. 5 is an elevational view of the structure shown in Fig. 3 and as viewed from left to right. Fig. 6 is a view of the lid in fully open position with the actuating spring tensioned and the tail ends of the spring disposed above the axial path of the lid retaining pintle. Fig. 7 is a sectional plan view of the lid proper as shown detached from the hood and on a line corresponding substantially to a line 7—7 of Fig. 6. Fig. 8 is a sectional view taken through the lid assembly and as viewed on a line corresponding substantially to a line 8—8 of Fig. 6. Fig. 9 is a vertical elevational view of a journal box and lid showing a

modified form of my invention. Fig. 10 is an end elevational view of the structure shown in Fig. 9 and as viewed from left to right.

Referring first to the structure shown in Figs. 1 to 8 inclusive, A indicates the journal box, B the hood or lever, C the lid, D the spring, E the hood retaining pintle, and F the lid retaining pintle.

The journal box A includes a body portion 10 having an opening 11 and above said opening 10 there is an upstanding hinge lug 12 having a plurality of faces as indicated at 13, 14 and 15 respectively. Extending through the said lug is a circular opening 16 for the reception of the pintle E and said lug immediately above the opening is provided with a channel shaped groove 17 in which the top of the lid is adapted to fit.

The hood or lever B includes an upper housing section 18 having side walls 19—19 adapted to lie on each side of the hinge lug 12 and extending outwardly from said walls are integral hub like ferrules 20 which constitute hinge eyes, each said hub at its outer end presenting an opening 21 facing towards the center of the hub assembly, said opening being preferably formed by a sector of the hub being cut away. The member B is formed with a body section merging into a pair of arms 22—22 which extend downwardly to a location approximately midway of the opening 11 and are there formed with slotted openings 23, said openings on the respective arms being disposed in transversely aligned relation for the reception of the pintle F. Intermediate the pintles E and F, the hood or lever B is formed with a recess of arcuate formation as indicated at 24 within which the coiled portions 25 of spring D are adapted to seat and within which the said spring is adapted to have limited turning movement.

The spring D, which is formed of spring wire, 40 includes a head 26 formed in the nature of a loop having a roller 27 associated therewith and the opposite end of the spring includes the two ends of the spring which are brought down in spaced relation on each side of the coil portion 25 to 45 present two tail ends as indicated at 28, said ends being preferably disposed in parallel relation when in normal released position as best indicated in Fig. 4. Said respective tail ends in the released position of the spring lie substantially 50 in the path of abutments 29 which are formed on the ends of the respective arms 22 and in order to impart tension in the spring, the tail ends of the springs are flexed around the inclined side faces 30 of the arms 22 and snapped into 55

- position above the abutments 29 and in seating relation with said abutment as shown in Fig. 3. With the tail ends of the spring seated on the abutments it will be readily appreciated that the 5 coils of the torsion spring will be slightly wound up and the roller will therefore be firmly held against the lug bearing faces. Said tail ends of the spring in being moved to tensed position move laterally as indicated in Fig. 4 by reason of 10 the inclined surfaces 30 which act in the nature of ratchets to automatically displace the spring ends laterally as the latter are moved in a clockwise direction as indicated by conventional dot and dash lines in Fig. 3. The flexing of the 15 spring ends may be conveniently effected by gripping an appreciable length of the spring in the jaws of a monkey wrench or other suitable gripping tool as indicated conventionally at 32 in Fig. 3.
- 20 The tail ends 28 of the spring are considerably longer than the head portion 26 of the spring, hence the tensing of the spring by individual movement of the respective tail ends is easily 25 carried out. The tensing of the spring being carried out in two distinct operations necessitates only overcoming one half of the spring's capacity at one time and in the present instance, the tail end portions being substantially twice the 30 length of the head portion, the force necessary to flex one of the individual tail ends is only approximately one fourth of the effort necessary to tension the spring by applying force at the roller 27. The long tail ends further provide the 35 necessary flexibility to spring the tail ends from one side of the abutment to the other.
- With the lid assembly in closed position, the roller 27 makes contact with face 13 of the lug and when the lid is in normal open position the roller contacts face 14 of the lug. Contact between face 15 and the roller is made whenever the lid is opened to its fullest possible extent. In order to have the pressure of the spring exert a closing action on the lid when the lid is in closed 40 position the roller 27 engages the face 13 at a short distance above the axis of the pintle E.
- The lid proper C includes a body portion 34 having an upstanding bracket portion 35 formed with an opening 36 adapted to register with 45 openings 23 to the extent of permitting the insertion of pintle E through said respective openings. On each side of the bracket portion 35 there is provided an abutment 37 disposed on the lid and lying substantially at the same radial distance from the pivot E as the axis of pivot F. Each abutment 37 presents a seat 38 lying substantially at the same level as the lower face of the opening 36, said seat being adapted to have the related tail end 28 seat thereon when the hood and lid are in operative relation.
- 60 At its upper end, the lid proper is formed with upward extensions 39 which are adapted to extend within the openings 21 of the hood. Said extensions 39 are spaced apart a sufficient distance to straddle the length of the pintle E in order to prevent endwise movement of said pintle when the lid and hood are in operative relation. The extensions 39 fit loosely in the openings 21 and thus permit of a limited pivotal movement of the lid about its pivotal connection F.
- 70 With the spring tensed as shown in Fig. 6, the tail ends 28 of said spring are out of the path of axial movement of the pintle F thereby permitting the latter to be inserted or withdrawn lengthwise from its operative position without interference with the spring tail ends. After the

pintle F has been applied the tail ends 28 are displaced from the abutments 29 and snap into seating relation with seats 38 of abutments 37 thereby transferring the pressure of the spring from the hood to the lid proper, the parts then assuming the position indicated by the full lines in Fig. 1. Said tail ends 28, when in engagement with abutments 37 effectively block endwise movement of the pintle F. The tension of the spring is normally sufficient to maintain the tail ends against the ends of the pintle F but in order to positively maintain said ends against lateral displacement there are provided walls 40 which lie adjacent to said tails and effectively prevent outward lateral displacement of the 15 same.

The abutment 37 and wall 40 are preferably united in an integral angle shaped bracket portion rising upwardly from the body of the lid, said angle shaped bracket having a cutaway portion 41 correspondingly in shape to the circular contour of the pintle F, thereby permitting axial movement of the latter member beyond and past the associated wall 40.

The assembly of the lid and hood with the 25 spring is preferably carried out in the following manner; the hood B is first mounted on the lug by means of the pintle E, the torsion spring D being loosely mounted in the housing part of the hood, and the hood is tilted back until such time as the housing contacts the rear end of the lug as shown in Fig. 3.

The next operation involves the tensioning of the spring by springing the tails 28 into position over the abutments 29 in the manner heretofore 35 explained. The lid proper is next placed in position by inserting the extensions 39 in the openings 21 and thereafter connecting the hood and lid through the medium of pintle F, after which the tail ends of the spring are displaced from 40 seating relation on abutments 29 and snap into position on seats 38 of the lid, thereby preventing axial movement of the pintle F and securely maintaining the parts in operative relation. The transfer of the spring tension from the hood 45 abutment to the lid abutment operates to yieldingly force the hood and lid apart to the extent permitted by the slot 23 and thereby eliminates undue rattling of the parts when the lid assembly is in open position. The loose connection 50 provided by the slot 23 permits a limited degree of universal movement between the hood and the lid whereby the lid is rendered self-adjusting to compensate for variations in manufacture of either the box or the lid parts.

The removal of the lid proper is carried out by reversing the operations above described, the transfer of the spring tension from the lid to the hood abutment being readily carried out by means of a suitable wrench or gripping tool or 60 by the insertion of a suitable levering tool under the tails of the spring. In the course of changing a lid proper, such as sometimes becomes necessary due to warping of the parts, it will be observed that my improved construction 65 enables the changing operation to be quickly carried out without the necessity of releasing the spring tension.

In the modification shown in Figs. 9 and 10, 100 indicates the journal box, 101 the hood, 102 the hood pintle, 103 the torsion spring, 104 the lid proper and 105 the lid pintle.

The lug of the journal box is indicated at 106. The hood 101 includes an upper housing portion 107 having laterally extending integral hinge fer- 75

tion before the lid is assembled and springing the tail ends into engagement with the hood, said hood having a seating abutment disposed beyond the opening for the lid pintle and with 5 which the tail ends of the spring are adapted to temporarily engage until such time as the lid and hood assembly is effected through the medium of the lid connecting pintle after which the tail ends of the spring are moved from the temporary 10 abutment and in blocking relation with respect to the lid pintle.

5. In combination, a journal box having a

hinge lug; a two piece lid assembly including a spring retainer pivoted to the lug and a lid proper pivoted to the retainer, said lid being mounted for limited pivotal movement; said retainer and lid being formed of separate parts; a pintle extending through the retainer and hinge lug; said lid having portions interlocking with the retainer to limit pivotal movement of the lid with respect to the retainer, said interlocking portions of the lid lying adjacent the ends of the retainer pintle 10 to prevent endwise movement of said pintle.

GEORGE B. DOREY.

rules 108, each formed at its outer end with a cutaway portion presenting an opening 109. The hood has an elongated body portion 110 extending towards the center of the lid assembly and 5 there terminating in a pair of arms 111—111, said arms being disposed in spaced relation and having at their outer end enlarged portions 113 formed with openings 114 through which the lid pintle 105 is adapted to extend. The body portion 10 is reinforced by means of vertical ribs 115 and outwardly of said ribs there are laterally extending hollow trunnion portions 116, which in effect constitute extensions of the enlarged portions 113. Said trunnions have bearing faces 15 117 and 118 disposed at different levels for the purpose as will hereinafter be pointed out.

The lid proper 104 has extensions 119 at each end thereof which seat in the openings 109 of the hood and at its central portion the lid has a bearing section 120 formed with an opening 121, the latter being adapted to register with openings 114 of the hood when the parts are in operative relation. The lid pintle 105 is adapted to extend through the openings 114 and 121 to 25 maintain the hood and lid proper in operative relation.

The spring 103 is preferably formed of a heavy wire having a pair of coil portions 122 with a centrally disposed loop portion 123 which forms a 30 head for the spring, said head having a roller 124 associated therewith. The respective ends of the spring extend downwardly presenting two tail ends 125 which are spaced apart and lie at the outer sides of the coil portions 122. The spring 35 is positioned between the lug and hood with the roller 124 bearing against the lug 106 and the tension in the spring is applied by individually springing the respective tail ends 125 to seat on the face 117 of the hood member. With the tail 40 ends of the spring seated on the faces 117 said portions of the spring are clear of the openings 114 and 121 and the spring ends are retained in such position until the pintle 105 has been inserted in place after which the individual ends of 45 the spring are displaced from the upper faces 117 and are caused to assume a seat on faces 118. The ends of the spring when in contact with lower faces 118 lie adjacent the ends of pintle 105 and effectively block endwise movement of the 50 latter member. The tail ends of the spring are effectively guarded against outward lateral displacement by means of walls 126 which lie adjacent to the tail ends when the latter are resting on the faces 118 of the hood.

55 In this embodiment of my invention, the lid is permitted a limited degree of universal movement to the extent permitted by the play in the pins and openings, which in normal circumstances is sufficient for all practical considerations. The 60 tensional force of the spring which is exerted at substantially the center of the lid operates to maintain the lid firmly against the opening.

What I claim is:

1. In combination, a journal box having a 65 hinge lug; a two piece lid assembly carried by the box, said assembly including a hood pivoted to the lug and a lid proper pivoted to the hood, said hood and lid being formed of separate parts; a pintle for securing the hood to the lug; a pintle 70 for securing the lid to the hood; said lid having portions adapted to lie adjacent the ends of the hood pintle to prevent endwise movement of said pintle, said portions of the lid being interlocked with the hood to limit pivotal movement between 75 the hood and lid; and a spring interposed be-

tween the lug and the hood, said spring having a coil portion bearing against the hood and having a head portion bearing against the lug and having tail ends extending towards the central part of the lid assembly to lie adjacent the respective 5 ends of the pintle connecting the hood and lid and secure the pintle against endwise movement.

2. In combination, a journal box having a hinge lug; a two piece lid assembly carried by the box, said assembly including a hood pivoted to 10 the lug and a lid proper pivoted to the hood; a pintle for securing the lid proper to the hood; a torsion spring between the hood and the lug, said spring having a coil portion and arms leading from said coil portion in opposite directions, one 15 of said arms being adapted to react against the lug and the other of said arms being adapted to be moved in a coil winding direction to tension the spring, said last named arm being in the form of two tail ends; an abutment on the hood 20 adapted to temporarily maintain the tail ends in spring tensioning position, said tail ends when in contact with the said abutment permitting assembly of the hood and lid proper by the insertion of the lid pintle; and a secondary abutment 25 on the lid proper adapted to form a seat for the tail ends after the lid proper is in position with the lid pintle applied, said tail ends when in engagement with the secondary abutment being adapted to block endwise movement of the lid 30 pintle.

3. In combination, a journal box having a hinge lug and a two piece lid assembly including a hood pivoted to the lug and a lid proper pivoted to the hood, said hood and lid having transversely aligned openings; a pintle adapted to extend through said respective openings; a torsion spring interposed between said hood and lug, said spring having a coil portion bearing on the hood and oppositely extending arms leading from said 35 coil portion and adapted to respectively engage with the lug and lid assembly, said last named arm being in the form of a pair of ends spaced apart and adapted to bear on the lid proper and secure the lid connecting pintle against endwise 40 movement; and abutment means on the hood adapted to temporarily receive the lid engaging arm of the spring and maintain said arm in a position above the lid pintle, in which position of the 45 spring ends assembly or disassembly of the lid proper with respect to the hood may be effected; and means on the lid proper adapted to lie outwardly of the spring ends when in operative relation and prevent outward movement thereof. 50

4. In combination, a journal box having a hinge lug associated therewith and having a two piece lid assembly including a hood pivoted to the lug and a lid proper pivoted to the hood, said hood and lid having transversely aligned openings adjacent the central part of the lid; a pintle adapted to extend through said respective openings and maintain the hood and lid in operative relation; a torsion spring interposed between the hood and lug, said spring including a coil portion adapted to bear on the hood and oppositely extending arms leading therefrom and adapted to respectively coact with the lug and with abutment means adjacent the central portion of the lid assembly, said last named arm including a pair of tail ends spaced apart and adapted to straddle the pintle connecting the hood and lid when the parts are in operative relation and prevent endwise movement of the said pintle; said spring being adapted to be tensioned by moving the tail ends in a coil winding direction. 65
